Hannah Luchs

United States Patent Office.

HANNAH LUCHS, OF WASHINGTON, DISTRICT OF COLUMBIA.

Letters Patent No. 96,820, dated November 16, 1869.

IMPROVEMENT IN FLUTING-MACHINES.

The Schedule referred to in these Letters Patent and making part of the same.

To all whom it may concern:

Be it known that I, HANNAH LUCHS, of the city of Washington, in the District of Columbia, have invented a new and useful Improvement in Fluting-Machines; and I do hereby declare that the following is a full and exact description thereof, reference being had to the accompanying drawings, and to the letters of reference marked thereon.

The nature of my invention consists in constructing a fluting-machine with an ordinary corrugated bed, but with a corrugated roller, detachable from the handles thereof, for the purpose of heating the same. The said roller being also provided with an aperture therein for the reception of a metallic heater, in order that when the character of the fire is such that the corrugated roller would probably become smoked or soiled in the process of heating it, which would soil the article, when being fluted, the heater may be withdrawn from the roller, and first heated, and afterward inserted therein, without the possibility of soiling the article in the process of fluting.

In the drawings—

Figure 1 is a side elevation of the base and corrugated roller.

Figure 2 is a longitudinal sectional view of the outer cylinder, and partially a sectional view of the inner cylinder, as denoted by the red line $z z$ in fig. 1.

A represents a metallic corrugated bed, whereon is placed the article, or that portion of the article which is to be fluted.

B represents a metallic corrugated roller, having a longitudinal aperture therein, a few lines smaller than the diameter of the roller, for the reception of the heater C; one end of said roller, or the one opposite the aperture for the reception of the heater aforesaid, being closed, as shown at b, the better to retain and adjust the heater in position, or to prevent its being pushed through the roller.

Said roller is also provided, at b', with a quadrilateral socket, for the reception of one of its handles, which handle projects through it into the heater C.

C represents the heater, which is inserted in the corrugated roller aforesaid, it being slightly smaller than the latter, to allow for its expansion, when heated.

Said heater is provided, at each lateral end, with a small socket, for the reception of the shanks of the handles of the roller aforesaid.

D and D' represent the handles of the corrugated roller, which handles are provided with quadrilateral shanks. The shank of the former D projects through a lateral aperture in the roller, and fits into a similar-shaped socket provided in the heater, but the handle D' is inserted directly into a quadrilateral socket, provided in the heater, as shown. The journals of these handles are round, at the knob, and rotate freely within the latter.

It will be observed that the handles D and D' are peculiarly designed, not only for removing the heater C, but for rotating the corrugated roller, which latter feature obviates the employment of a crank.

I do not claim the hollow cylinder, for the reception of the heater, nor the heater, save in its peculiar adaptation to the handles and corrugated roller aforesaid, as I am aware that said features have hitherto been patented.

Claim.

The combination and arrangement of the adjustable handles D and D', the heater C, and corrugated roller B, of a fluting-machine, substantially as and for the purpose specified.

H. LUCHS.
